H. C. HARRISON.
RADIATOR CORE.
FILED DEC. 3, 1921

UNITED STATES PATENT OFFICE.

HERBERT C. HARRISON, OF LOCKPORT, NEW YORK, ASSIGNEE TO HARRISON RADIATOR CORPORATION, A CORPORATION OF NEW YORK.

RADIATOR CORE.

Application filed December 3, 1921. Serial No. 519,728.

To all whom it may concern:

Be it known that I, HERBERT C. HARRISON, a subject of the King of Great Britain, residing at Lockport, in the county of Niagara 5 and State of New York, have invented certain new and useful Improvements in Radiator Cores; and I do hereby declare the following to be a full, clear, and exact description of the invention, such as will enable others skilled in the art to which it 10 appertains to make and use the same.

This invention relates to radiator constructions, and has for its object to provide a radiator core which will be simple to construct, and more efficient in operation than those heretofore proposed.

With these and other objects in view, the invention consists in the novel parts and combinations of parts constituting the core, 20 all as will be more fully hereinafter disclosed and particularly pointed out in the claims.

This invention is an improvement over my prior Patent No. 1,314,263, dated August 26, 1919, and entitled "Radiator constructions."

Referring to the accompanying drawings forming a part of this specification, in which like numerals designate like parts in all the views:

Figure 1 is a sectional view illustrating 30 the air cells and water passages in accordance with the construction disclosed in my said former patent;

Figure 2 is a plan view of one of the unit plates illustrated in my said former patent;

Figure 3 is a sectional view of the parts shown in Figure 2;

Figure 4 is a sectional view similar to Figure 1, but illustrating the present improved construction of radiator units and 40 water passages;

Figure 5 is a plan view of one of the unit plates employed in making the radiator unit of Figure 4;

Figure 6 is a sectional view of the parts 45 shown in Figure 5; and

Figure 7 is a conventional view of the radiator made in accordance with the present invention.

In order that this invention may be the 50 better understood and the more easily distinguished from the construction of my said former patent, it is said:

In my prior patent above referred to, the radiator unit is composed of a pair of corrugated unit plates 1 and 1' having the

folded fin portions 2, and the offset edges 3. This said pair of plates are disposed with their fin portions 2 pointing in opposite directions as indicated and are separated by the perforated corrugated division plate 4, 60 as shown, so as to form a double row of air cells 5, while an outer plate 6 of an adjacent unit contacts with the plate 1 of the said pair of plates to form the zigzag water passage 7, all as is well known. 65

In other words, the offset edges 3 carried by an outer plate 1 of the one unit contact along the zigzag line 15, Fig. 1, with the offset edges 8 of the outer plate 6 of an adjacent unit, to form the zigzag water passages 70 7, as plainly illustrated. It has been found, however, that a straight water passage is much to be desired in radiators of this character, for the efficiency of the radiator as a whole is increased thereby. 75

But in order to form the desired straight water passages and still retain the well known hexagonal shape of the air cells which characterize the radiators of my said patent, it is found necessary to omit the said 80 offset edges 3 or 8 from the outer plates forming the radiator units. Therefore, in carrying out this invention, the thin brass plates 11 and 11' out of which the radiator units are formed, are uniformly corrugated 85 as in my former patent, but without offsetting their edges at all. That is, said plates are provided with the two sides 9 and 16 of the hexagon, separated by the ridges 17, precisely as is the case in my said former patent, 90 and also with the fin portions lettered 10 in the present invention formed by bending the metal upon itself.

In other words, so far as is now described, the unit plates of the new invention do not 95 differ from the unit plates of my prior construction except for the omission of the offset edges 3. But if two contacting unit plates of different units were brought together without these offset edges, and with 100 no other difference of construction over said prior patent, there would be no water passage formed, for the ridges 17 of the one plate would fit from end to end of the air passages in the depressions between two 105 ridges 17 in another plate, and no space would be left for the water to pass at all. Accordingly, in order to provide the desired straight water passages, I mash down or flatten down the ridges 17 in my new plates 11 110

and 11' in a plurality of rows to form a plurality of individual flattened surfaces 13 as plainly shown in Figures 5 and 6. These said flattened surfaces 13 in one unit plate 5 11, see Figure 4, alternate with the flattened surfaces 13 in another unit plate 20 in such a way that a straight water passage 21 is produced.

Stated in other language, a pair of unit plates 11 and 11' are assembled, in carrying out the present invention, with their fins 10 opposing each other and separated by a division plate 4 precisely as was done in my said former patent, while an outer unit plate 15 20 of an adjacent unit is brought into contact with one of said unit plates 11, so that the short ridge portions 17 of one unit plate 11 will fit into the depressions between a pair of ridge portions 17 in an adjacent 20 unit plate 20 along the zigzag line 23 formed by the corrugated surfaces 9 and 16, thus causing the rows of flattened surfaces 13 to alternate with each other on said opposing unit plates and to form the straight 25 water passage 21.

It will now be clear that this invention differs from that of my prior patent in that the corrugated surfaces 9 and 16, see Figure 1, are at a plurality of points along 30 their lengths flattened in toward the air cells 5, so that they would occupy the dotted line position 30 in the plate 1 and the dotted line position 31 on the plate 6, if said surfaces 13 were provided in the old construction 35 to form the straight water passage shown in Figure 4. But in such case, the offset edges 3 and 8 would cause said passage to be unduly wide; therefore said offset edges are preferably abolished in the 40 new construction.

The production of this said straight water passage, 21, in the present invention, produces the following desirable results:

It increases the flow of water to the desired volume, and therefore the capacity of 45 the radiator. Further, an inspection of Figure 6 will show that the flattened portions 13 extending inward toward the air cells 5 form curved obstructions 25 to the 50 passage of air, which are separated by the wider spaces 26, and thus is the air broken up and balloted across the air passages to a greater degree in its travel through the 55 radiator than is the case when these curved obstructions are not present. The entire 60 radiator core, 28, when placed in the radiator frame 29 does not differ in appearance from that of my former patent and is found to possess all of the advantages of said prior core together with a higher operating efficiency.

What is claimed is:

1. The herein described radiator unit comprising outer walls made from single strips of corrugated metal having folded oppositely disposed fin members; and ridges between said fin members provided with flattened portions along their length to form one half wall of a straight water passage, substantially as described. 70

2. The herein described radiator unit comprising a division plate and outer walls each composed of a single strip having folded fin members and a pair of corrugated surfaces joined by a ridge member 75 extending from edge to edge of the strip between each adjacent pair of fins, said ridge members provided with flattened portions adapted to form one wall of a straight water passage and said fins being oppositely disposed and separated by said division plate to form a double row of air passages, substantially as described. 80

3. The herein described new radiator core comprising a plurality of radiator units, 85 the outer plates of which are corrugated to form flat surfaces separated by ridges and bent upon themselves to form fin members constituting, with said flat surfaces, the walls of the air passages; and the said 90 ridges being provided along their lengths with portions flattened in toward said air passages to form straight water passages between adjacent units, substantially as described. 95

4. A radiator unit comprising a pair of sheet metal plates bent and closed upon themselves to provide oppositely projecting spaced fin portions whose sides form parallel walls of air passages, said plates being 100 also bent between said fins to provide ridges extending away from said fins and air passages, said ridges being flattened inwardly toward said air passages to form portions of straight water passages, and a perforated, 105 corrugated division plate located between said first named plates contacting with said fins, substantially as described.

5. A radiator made up of sheet metal plates, bent to form air passages, portions 110 of which are hexagonal in cross section, said plates having distributed along said air passages flattened portions, and bent upon themselves to form oppositely disposed fins, and said plates being connected in parallel 115 to cause said flattened portions to form straight water passages, substantially as described.

In testimony whereof I affix my signature.

HERBERT C. HARRISON.
